Primary Examiner — Cynthia M Chin*(74) Attorney, Agent, or Firm* — Dunlap, Bennett & Ludwig(57) **CLAIM**

The ornamental design for a transom saver, as shown and described.

DESCRIPTION

FIG. 1 is a perspective front view of a transom saver, shown in use supporting an outboard motor;

FIG. 2 is a front elevation view of the transom saver; the rear elevation view being an identical image thereof;

FIG. 3 is a left side elevation view of the transom saver; FIG. 4 is a right side elevation view of the transom saver; and,

FIG. 5 is a top plan view of the transom saver.

The broken lines shown in FIG. 1 illustrate the outboard motor supported by the transom saver, the outboard motor forms no part of the claimed design.

The broken lines shown in FIG. 4 illustrate cavities in the transom saver that form no part of the claimed design.
